(57) **CLAIM**

The ornamental design for a thermoelectric heat pump, as shown and described.

DESCRIPTION

FIG. 1 is an upper elevation view of a thermoelectric heat pump showing our new design;

FIG. 2 is a lower perspective view of the thermoelectric heat pump of FIG. 1;

FIG. 3 is a top plan view of the thermoelectric heat pump of FIGS. 1-2;

FIG. 4 is a bottom plan view of the thermoelectric heat pump of FIGS. 1-3;

FIG. 5 is a left side elevation view of the thermoelectric heat pump of FIGS. 1-4;

FIG. 6 is a right side elevation view of the thermoelectric heat pump of FIGS. 1-5;

FIG. 7 is a rear elevation view of the thermoelectric heat pump of FIGS. 1-6; and,

FIG. 8 is a front elevation view of the thermoelectric heat pump of FIGS. 1-7.

Throughout the Figures, the dashed broken lines are included for the purpose of illustrating environment of the design and form no part of the claimed design, and the dot-dash broken lines represent boundaries of the claimed design and form no part of the claimed design.
